SPRING FOR RATCHET MECHANISMS

Led L. Richardson, Cleveland, Ohio, assignor to
 The Cleveland Rock Drill Company, Cleveland,
 Ohio, a corporation of Ohio

Application May 9, 1932, Serial No. 610,102

1 Claim. (Cl. 267—1)

This invention relates broadly to ratchet mechanism but more specifically to improvements in the springs associated with the ratchet mechanism used in connection with rock drills.

In constructing a ratchet mechanism for rock drills, it is the common practice to provide a rifled bar having a head within which is drilled a plurality of restricted bores. Co-operating with this rifled bar, there is a ratchet ring which is connected thereto by a plurality of pawls actuated by a spring pressed plunger longitudinally movable within the restricted bores. Heretofore, the springs were wound substantially cylindrical with an outside diameter somewhat smaller than the diameter of the bore, permitting thereby the frictional engagement of its coil with the inner peripheral wall of the bore. Due to the rapid compression and expansion of the spring, the coils thereof, rubbing against the inner wall of the bore, would prematurely wear and cause the breakage of the spring, increasing thereby the cost of operation.

It is among the objects of this invention to provide a ratchet mechanism for rock drills with the spring having the coils subjected to mechanical stress, being free of frictional engagement with the inner peripheral wall of the bore within which the spring is mounted, preventing thereby a premature wear and breakage of the spring as well as reducing the cost of operation.

Other objects more or less ancillary to the foregoing and the manner in which the above mentioned object is realized, will appear in the following description, which considered in connection with the accompanying drawing, sets forth the preferred embodiment of the invention.

In the drawing:

Fig. 1 is a longitudinal view, partly in section, of a rock drill representative of one of the types of machines in which the ratchet mechanism may be incorporated.

Fig. 2 is an enlarged cross sectional view taken in a plane indicated by line 2—2 in Fig. 1, illustrating the ratchet mechanism with the springs incorporated therewith.

Fig. 3 is an enlarged longitudinal view of the spring.

The embodiment herein chosen to illustrate the present invention is a rock drill of the hammer type which comprises a cylinder 10 within which there is mounted a piston 11 formed with an extended stem portion or hammer 12, adapted to co-operate with the head of a cutting tool 13 in the manner customarily employed in percussive rock drills. Mounted within the rearward end

of the cylinder, there is a valve block 14 having a valve 15 reciprocable therein for controlling the admission of motive fluid within the cylinder 10 to actuate the piston 11. The valve block 14 is maintained within the cylinder 10 by the co-operation of a back head 16 which is secured by a pair of side bolts (not shown). 5

During the drilling operation, i. e. when the hammer 12 is delivering its blows to the cutting tool 13, it is necessary to rotate the cutting tool. 10 For this purpose there is provided a rotation mechanism, comprising a rifle bar or stem 17 which is slidably engageable within the head of the piston 11 in a bore of complementary configuration. The rifled stem 17 is provided with an 15 enlarged head 18 within which there is drilled a plurality of restricted bores 19. Within each of said bores there is reciprocably disposed a plunger 20 subjected to the action of a compression spring 21 disposed rearwardly thereof. Toward its ends, 20 the spring is manufactured with enlarged coils of an outside diameter substantially equal to the diameter of the bore 19, and capable of engagement with the inner peripheral wall of the bore 19, for guiding the spring in axial alignment with the plunger 20. These last coils are closed in upon each other as shown at 22 for the purpose which will be explained later. Pivotal secured within the enlarged head 18, there is a plurality 30 of pawls 23 upon which the spring pressed 30 plungers 20 are acting to maintain the free end thereof away from the enlarged head 18. This head and its appurtenances is encompassed within a ring 24, having its inner peripheral wall provided with a plurality of longitudinally disposed 35 teeth 25 with which the free ends of the pawls 23 are capable of intermittent engagement.

During the forward stroke of the piston 11, the rifled bar 17, by reason of its engagement with the piston 11, is made to rotate in one direction. During this motion, the free end of the pawls 23 in engagement with the plunger 20, will pass over the teeth 25 and will cause a rapid compression and expansion of the springs 21. The working coils of the spring, i. e. the coils 45 intermediate the enlarged coils thereof, being of an outside diameter smaller than the internal diameter of the bores 19, are free from frictional engagement with the inner peripheral wall of the bore 19 and consequently are not subjected 50 to wear. The enlarged coils in engagement with the inner peripheral wall of the bore 19 to guide the spring in axial alignment therewith, are closed in upon each other to prevent the compression or expansion thereof. These enlarged 55

coils are subjected to wear but are free of mechanical stress, preventing thereby the combination of wear and mechanical stress resulting in the breakage of the coils.

5 Although the foregoing description is necessarily of a detailed character in order to completely set forth the invention, it is to be understood that the specific terminology is not intended to be restrictive or confining and it is to be further understood that various rearrangements of parts and modification of structural detail may be resorted to without departing from the scope or spirit of the invention as herein claimed.

10 I claim:

15 A helical compression spring formed of com-

pressible and non-compressible coils, said non-compressible coils constituting the ends of said spring, the diameter of said last coils being substantially equal to that of a bore within which said spring may be disposed, permitting thereby the engagement of said last coils with the inner wall of said bore so as to center said spring therein, the diameter of each of said compressible coils being substantially equal but smaller than that of said non-compressible coils, thus causing 10 an equal deflection of the compressible coils when a load is applied to the spring and preventing the possible engagement of said compressible coils with the inner wall of said bore.

LEO L. RICHARDSON. 15
